Fig. 18.

Fig. 19.

FIG. 1 is a perspective view of a luminaire embodying my new design;

FIG. 2 is a top plan view thereof;

FIG. 3 is a front elevational view thereof;

FIG. 4 is a side elevational view thereof;

FIG. 5 is a bottom plan view thereof;

FIG. 6 is a rear elevational view thereof;

FIG. 7 is a front elevational view of a second embodiment of my design, being a composite of three of the luminaires shown in FIGS. 1-6;

FIG. 8 is a top plan view thereof;

FIGS. 9 through 13 are top plan views on a reduced scale of further embodiments of my design, each being a composite of luminaires shown in FIGS. 1 through 6;

FIGS. 14 through 19 are enlarged perspective views of the brackets of the embodiments shown in FIGS. 8 through 13 respectively, the luminaires being omitted for purposes of disclosure.

I claim:

The ornamental design for a luminaire, as shown and described.
